UNITED STATES PATENT OFFICE.

JOHN MERLEY, OF CANTON, OHIO, ASSIGNOR, BY MESNE ASSIGNMENTS, TO THE UNION
TRUST COMPANY OF PITTSBURGH, TRUSTEE.

SILO AND BUILDING-TILE THEREFOR.

1,076,597.

Specification of Letters Patent.

Patented Oct. 21, 1913.

Application filed July 28, 1911. Serial No. 641,162.

To all whom it may concern:

Be it known that I, JOHN MERLEY, a resident of Canton, in the county of Stark and State of Ohio, have invented a new and useful Improvement in Silos and Building-Tiles Therefor, of which the following is a full, clear, and exact description, reference being had to the accompanying drawings, in forming part of this specification, in

10 which—

Figure 1 is a horizontal section of a silo embodying my invention taken through one of the joints; Fig. 2 is a side elevation of a portion of a silo; Fig. 3 is a detail sectional view showing several assembled tiles, the plane section being on the line III—III of Fig. 4; Fig. 4 is a fragmentary view partly in side elevation and partly in section of a portion of a silo wall; and Fig. 5 is a side view illustrating a modification.

15 My invention has relation to silos and to building tiles for use in the construction thereof, and is designed to provide a tile which can be cheaply manufactured and which is provided with means of improved character for connecting it to adjacent upper and lower tiles in such a manner that the use of exterior bands or other holding devices around the silo structure is avoided.

20 My improved tile also provides means by which silos may be rapidly and cheaply constructed and does away with the use of expensive connecting devices and provides connecting means which are not easily broken and which can be quickly applied.

25 The nature of my invention will be best understood by reference to the accompanying drawings, in which I have illustrated the preferred embodiment thereof, and which will now be described, it being premised, however, that various changes may be made in the details of construction, without departing from the spirit and scope of my invention as defined in the appended claims.

30 My improved tile, designated by the numeral 2, is of hollow segmental form, preferably of terra cotta, the central opening extending vertically through the tile from end to end. The lateral faces 3 of the tile are substantially radial, their inner narrow ends 4, are concave, and their outer ends 5 are slightly convex, so that when assembled in the manner hereinafter described, they

will form a hollow cylindrical silo structure. The tiles are also provided on their lateral faces with bonding grooves or recesses 6, to receive the cement or other filling 7, which is placed between the tiles in setting them up. Each tile is also formed with inward projections or swells 8, having holes 9 extending vertically therethrough from top to bottom, these holes being provided for the purpose presently to be described.

35 In building a silo structure with my improved tiles, successive circular courses are laid one above another, the tiles of adjacent courses being so placed as to break joints in the adjacent courses. A suitable cement is placed between the vertical lateral faces of the tiles and also between the horizontal courses. The successive courses are firmly connected to each other either by means of relatively short dowels 10, seated in the holes 9 and extending across the horizontal joints, or by means of vertical rods 11. (see Fig. 5) 40 which may extend entirely through the vertical holes 9 of two or more adjacent courses. When these rods are employed, they are preferably arranged in overlapping sets, as shown in Fig. 5. The usual vertical door opening 12 is left at one side of the silo structure and the tiles at the edges of this opening are connected across the opening by means of tie bars 13, which are secured to the tiles by means of pins or dowels inserted 45 in the holes 14, provided therefor, these holes 14 being partly formed in interior projections 15 of the tiles.

50 16 designates the usual doors to receive which the tiles adjacent to the upper opening may have their inner corners cut away, as shown at 17, in Figs. 1 and 3.

55 As a further means of bonding the horizontal courses of the tiles, a layer or layers of wire fabric, such as indicated at 18 in Fig. 1, may be placed between adjacent courses, the dowel pins or vertical rods extending through such fabric and the cement also bonding in the meshes thereof. In order to more effectively break the joints, some 60 of the tiles may be of greater width than others. Thus, in Figs. 3 and 4, I have shown the tiles adjacent to the door opening as being considerably wider than the other tiles.

65 105 The advantages of my invention will be

apparent, since it provides means whereby a silo of strong and durable character may be readily and cheaply constructed.

I claim:

5. 1. A building tile for silos and the like of hollow segmental form, said tiles having closed ends and sides and an internal projection at each corner of the tile formed with vertical perforations extending therethrough 10 to receive connecting devices; substantially as described.
15. 2. A building tile for silos and the like of hollow segmental form, said tiles being closed at both ends and both sides, a plurality of internal projections formed with vertical perforations extending therethrough to receive connecting devices, the sides of the tile having vertical grooves formed 20 therein for the reception of binding material; substantially as described.
25. 3. A silo composed of superimposed horizontal courses of tiles, each tile having a vertical opening extending therethrough, said tiles being closed at both ends and both sides, each of said tiles having formed in at least one of its sides a vertical groove registering with a similar vertical groove in an adjacent tile, bonding material within said 30 grooves and at least four integral projections formed on each tile at the corners thereof, said projections having vertical perforations therethrough, two of the perforations in one tile registering with two perforations in the tiles in adjacent courses, the others registering with perforations in other tiles in said courses, and connecting devices in said perforations for connecting the tiles in one course with the tiles in adjacent courses; substantially as described.

4. A silo composed of superimposed horizontal courses of tiles, each tile having a vertical opening extending therethrough, the tiles of one course being in staggered relation with the tiles in adjacent courses so that there is a single air space formed by 40 said openings between the inner and outer shells of the silo, there being a plurality of vertical perforations through the walls of each of the tiles, the perforations through the tiles in one course registering with perforations through tiles in adjacent courses, 45 and securing devices in said perforations for securing the tiles of one course to the tiles in adjacent courses; substantially as described.

5. A silo composed of superimposed horizontal courses of tiles, each tile having a vertical opening extending therethrough, the tiles of one course being in staggered relation with the tiles in adjacent courses so 50 that there is a single air space formed by said openings between the inner and outer shells of the silo, there being a plurality of vertical perforations through the walls of each of the tiles, the perforations through the tiles in one course registering with perforations in adjacent courses, securing devices in said perforations for securing the tiles of one course to the tiles in adjacent 55 courses, and means for securing adjacent tiles in the same course to each other; substantially as described.

In testimony whereof, I have hereunto set my hand.

JOHN MERLEY.
